UNITED STATES PATENT OFFICE

2,542,073

SHEET CONTROLLED INTERRUPTER FOR
OFFSET PRINTING PRESSESRoy Aberle, Portland, Maine, assignor to South-
worth Machine Company, Portland, Maine, a
corporation of Maine

Application September 20, 1946, Serial No. 698,252

10 Claims. (Cl. 101—144)

1

This invention relates to printing presses and is most particularly applicable to sheet-fed lithographic offset presses. Among the objects of the invention are to improve the general organization of a press and its driving gearing; to improve latching mechanism controlling the pressure at the offset cylinder; to improve feeding, transfer and delivery sheet conveyors of the press and their cooperative action; to improve mechanism for aligning the incoming sheets delivered to the press by a sheet-feeder mechanism and to improve the timing of reception of these sheets by the feeding conveyor of the press; to provide for subjecting the side of a sheet which has contacted with the offset cylinder to a supplemental printing operation such as serial numbering; to subject the side of the sheet opposite to the side which has contacted with the offset cylinder to a printing operation by providing a supplemental mechanism for offsetting an inked image onto the impression element of the press; to provide an improved control over the lowering of the stack of delivered sheets in accordance with the action of the sheet-feeder mechanism; and to improve mechanism for aligning the sheets delivered to the stack.

The invention further aims to improve plate dampening mechanism and inking mechanism of the press and the drives for these mechanisms, and further to improve these mechanisms in such a way as to provide better access to the inner portions of the press, such as the main cylinder, the ink form rolls and the supplemental mechanism for offsetting an inked image onto the impression element.

The invention further aims to provide improved detection of failure of sheet feed and an improved system of control of the principal operative parts of the press and also of a sheet counter. The invention also has for an object to provide for an improved system of control of the sheet-feeder.

Further objects of the invention and features of improvement will be apparent from this specification and its drawings wherein the invention is explained, by way of example, by the description of a specific mechanism embodying the invention.

In the drawings:

Fig. 1 is a diagram showing the main rolls of 50 the press;

Fig. 2 is a diagram, looking in the same direction as Fig. 1, showing certain of the driving connections and showing the pile delivery;

Fig. 3 is a vertical sectional view, looking in 55

the same direction as in Figs. 1 and 2, showing sheet-conveying mechanism and mechanism for printing upon (more specifically, numbering) the previously-printed sheets that are carried by the sheet-conveying mechanism;

Fig. 3a is a section, on a reduced scale, on the line 3a—3a of Fig. 3;

Fig. 4 is a view taken from the right or entering side of the press, that is, from the right of 10 the press as viewed in Figs. 1, 2 and 3, constituting a front view of the side jogger mechanism;

Fig. 5 is a vertical sectional view taken on the line 5—5 of Fig. 4;

Fig. 6 is a plan view of the right hand jogger 15 unit of Fig. 4;

Fig. 7 is an assembly view showing the side jogger mechanism, paper stop, the chain of the first conveyor means, and the interconnections between these parts;

20 Fig. 8 is a fragmentary view of the gripper bar of the first conveyor means, showing a fragment of the chain of the first conveyor means;

Fig. 9 is a fragmentary vertical sectional view taken on the line 9—9 of Fig. 8, showing the 25 paper stop and mechanism for opening and closing the grippers of the gripper bar of Fig. 8;

Fig. 10 is a vertical sectional view taken on the line 10—10 of Fig. 8 showing one of the grippers of the first conveyor means;

30 Fig. 10a is a view similar to Fig. 10 showing the jaw of one of the grippers of Fig. 10 in an open position;

Fig. 11 is a vertical sectional view of the press taken from the opposite point of view from Figs. 1, 2 and 3 and looking outward toward one of the side frames, showing especially the mechanism for applying pressure to the offset cylinder, many of the mechanisms of the press being omitted;

Fig. 12 is a view similar to Fig. 11 on a larger 40 scale, showing also an electric switch responsive to separation of the main and offset cylinders;

Fig. 13 is a fragmentary vertical sectional view taken on the line 13—13 of Fig. 11 on a larger scale;

45 Fig. 14 is a fragmentary vertical sectional view on the line 14—14 of Fig. 13;

Fig. 15 is a diagrammatic view taken from the same point of view as Figs. 1, 2 and 3, and on a larger scale, showing the first conveyor means transferring a sheet to the second conveyor means;

Fig. 16 is a view similar to Fig. 15 showing the second conveyor means transferring a sheet to the third conveyor means;

Fig. 17 is an assembly view of a portion of the

2

second or transfer conveyor means, all except one of the several grippers being omitted for simplicity of illustration and this gripper being shown in the open position;

Fig. 18 is an end view of the second conveyor means;

Fig. 19 is a vertical sectional view taken generally on the line 19-19 of Fig. 17;

Fig. 20 is a fragmentary sectional view taken on the line 20-20 of Fig. 19 showing a movable jaw of one of the grippers of the second conveyor means;

Fig. 21 is a vertical sectional view taken on the line 21-21 of Fig. 20, showing also in broken lines the closed position of the gripper jaw;

Fig. 22 is a view taken on the line 22-22 of Fig. 3 showing one of the gripper bars of the third conveyor means;

Fig. 23 is a fragmentary sectional view taken on the line 23-23 of Fig. 22;

Fig. 24 is a fragmentary sectional view taken on the line 24-24 of Fig. 22 showing one of the movable jaws of the gripper bar of Fig. 22;

Fig. 25 is a diagram in the nature of a plan view showing numbering mechanism and a portion of a chain of the third conveyor of the press;

Fig. 26 is a fragmentary view in the nature of an elevation of the platen roll of the numbering mechanism and its driving connections, as viewed from right to left in Fig. 3;

Fig. 27 is a diagram taken from the right side of Fig. 26 and from the opposite point of view from that of Fig. 3, showing the driving connections for the one or more numbering units and for the platen roll of the numbering mechanism;

Fig. 28 is a sectional view taken on the line 28-28 of Fig. 26, showing mechanism for controlling the platen roll of the numbering mechanism;

Fig. 29 is a diagram in the nature of a side elevation of the paper stack and paper stack platform of the feeding apparatus for use with the press;

Fig. 30 is a diagram in the nature of a plan view of a fragment of the feeding apparatus of Fig. 29;

Fig. 31 is a plan view of corner jogger mechanism at the pile delivery of the press;

Fig. 32 is a fragmentary view similar to Fig. 31, showing a pair of corner jogger abutments retracted from the paper stack;

Fig. 33 is a vertical sectional view taken on the line 33-33 of Fig. 31;

Fig. 33^a is a fragmentary vertical sectional view taken on the line 33^a-33^a of Fig. 31 showing a pair of corner jogger abutments;

Fig. 34 is a side elevation, taken from inside the main frame of the press, looking in the same direction as in Figs. 1, 2 and 3, showing one side of the dampening mechanism;

Fig. 35 is a fragmentary side elevation, taken from inside the movable frame of the dampening mechanism;

Fig. 36 is a fragmentary side elevation, taken from the opposite side of the press from Fig. 34, and showing the opposite side of the dampening mechanism;

Fig. 37 (on the same sheet as Fig. 7) is a diagram of control circuits for many of the elements of the press;

Fig. 37^a (on the same sheet as Fig. 46) is a diagram showing the control of the feeder pump motor;

press showing the upper movable frame of the press raised to give access to normally inaccessible parts;

Fig. 38^a is a detail of a portion of mechanism for raising and lowering the upper movable frame

Fig. 38 is an elevation of the upper part of the press;

Fig. 39 is an elevation, partly broken away and partly diagrammatic, showing the form rolls for the main cylinder and mechanism for controlling the operation of these form rolls;

Fig. 40 is a detail view of the control mechanism of Fig. 39, viewed from the left side;

Fig. 41 is a fragmentary plan view of the supplemental cylinder for offsetting onto the impression segment of the main cylinder, and the eccentric shaft of this supplemental cylinder;

Fig. 42 is a sectional view taken on the line 42-42 of Fig. 41;

Fig. 43 is a detail view, taken from the opposite point of view from that of Fig. 1, showing the connection between the shaft of the main cylinder and the eccentric shaft of the supplemental cylinder of Fig. 41 and showing mechanism for controlling the operation of the supplemental cylinder;

Fig. 44 is a detail view of the control mechanism of Fig. 43, taken from the left of Fig. 43;

Fig. 45 is a fragmentary view showing the hanger for one of the form rolls and portions of this form roll, the cooperating distributor roll, the upper movable frame and the upper stationary frame;

Fig. 46 is a sectional view taken on the line 46-46 of Fig. 45;

Fig. 47 is a fragmentary view showing the supplemental cylinder and the mounting for its associated form roll and transfer roll, and also showing mechanism for holding this form roll in an inactive position; and

Fig. 48 is a fragmentary view showing the form roll for the supplemental cylinder.

45 Outline of general organization of machine

The illustrated machine contains many of the features of the machines of my prior Patents Nos. 2,140,256 and 2,257,490 and is especially adapted to be used in combination with the sheet-feeding mechanism shown in my copending application Serial No. 590,225, filed April 25, 1945 which matured into Patent No. 2,497,849, February 21, 1950, a continuation-in-part of application Serial No. 490,556, filed June 12, 1943 (now abandoned).

The main frame of the press includes opposite interconnected side plate sections 25 which are preferably flanged as at 25^a at their lateral margins (Figs. 11 and 25), the flanges serving to cover and protect various gears, chains, bearings and control mechanisms that are located adjacent to the two side plates 25.

Sheets fed successively by feeding mechanism such as that of said applications enter the machine from the right as shown in Figs. 1, 2 and 3 are stopped by stop fingers 30, Figs. 4, 7 and 9, are laterally aligned by side jogger mechanism indicated generally at 31 in Figs. 4 to 7 inclusive, and are gripped by gripper fingers 32, Figs. 8 and 10, on a gripper bar 33 carried by chains 180. The course of chains 180 is indicated in Figs. 1, 2 and 3.

The sheet is carried by the traveling gripper bar 33 to and partly around a rubber covered

5

offset cylinder 40, the offset cylinder having a recess adapted to receive the gripper bar.

As shown in Fig. 1 offset cylinder 40 cooperates with a main cylinder indicated generally at 42. Main cylinder 42 comprises opposite end portions 42a mounted on a shaft 166, a lithographic plate holder segment 43 having hub portions 43a also mounted on the shaft 166, and an interchangeable impression segment 44 detachably secured to the opposite end portions 42a. Depending upon the character of the work being done, impression segments having surfaces of various materials may be used as more fully described hereinafter.

As explained in the above patents, a lithographic plate on segment 43 offsets an image onto the offset cylinder 40, the sheet is then carried in between the offset cylinder and the impression segment 44 of the main cylinder, which results in the image being printed from the offset cylinder 40 onto the lower surface of the sheet.

The timing and arrangement of the main and offset cylinders and the feeding mechanism, paper stop fingers, side jogger mechanism and gripper bar 33 is such that a sheet to be printed is presented to the nip between the offset and main cylinders at each revolution of the main cylinder, or in other words, at each second revolution of the offset cylinder.

The main cylinder 42 is provided with plate-dampening mechanism indicated generally at 50 and plate-inking mechanism indicated generally at 55 so as first to dampen the water-receptive blank portions of the lithographic plate and then to ink the ink-receptive image-carrying portions during the time that the impression surface 44 is cooperating with the offset cylinder 40. Further rotation of the main cylinder then brings the dampened and inked lithographic plate on segment 43 into position to offset its inked image onto the rubber surface of the offset cylinder 40.

A supplemental roll 60, for instance carrying a rubber plate having raised letters, is arranged to offset onto the otherwise blank surface of the impression segment 44 of the main cylinder. The image thus transferred to the impression surface 44 is then printed onto the upper surface of the sheet simultaneously with the printing onto the lower surface of the sheet by offset cylinder 40.

Leaving the nip between the offset cylinder 40 and the impression segment 44, the printed sheet is released by the grippers of bar 33 and simultaneously gripped by a circularly moving second set of grippers 70, (Figs. 3 and 15), which move around axis 71 (Fig. 1), and at the end of an approximately 90° circular travel release the sheet and transfer it to third grippers 80, (Figs. 3 and 16), which are carried by chains 142 in a generally triangular path, as shown in Figs. 1 and 3.

On the first or downwardly inclined portion of this triangular path away from the offset cylinder, the sheet may be subjected to a further printing operation. Mechanism for such further printing preferably comprises, as shown in Fig. 3, one or more rotating serial numbering units 90 and cooperating platen rolls 91 between which the sheet is carried (Fig. 3) so that the sheet is numbered on its lower surface upon which it had previously received an impression from the offset cylinder.

The chain-carried third grippers 80 then carry the sheet onto the lower horizontal run of their triangular path, in which the grippers are caused to open and drop the sheet, with its offset printed

6

and numbered surface uppermost, onto an automatically lowered stack 100 (Fig. 2) on a platform 101 on which the newly arrived sheet is aligned both longitudinally and transversely by corner-jogging mechanism indicated generally at 120.

Drive to third, second, and first paper-carrying grippers, offset and main cylinders, sheet stop and side joggers.

The driving connections to many of the main parts of the machine are shown diagrammatically in Fig. 2. An electric motor 120 is connected by a V-belt 121 to drive a variable-diameter V-pulley 122 on a counter-shaft 123. A similar variable-diameter V-pulley on counter-shaft 123 drives a further V-belt 125 which in turn drives a pulley 126 on counter-shaft 127. Axial adjustment of the pulley sections which comprise the V-pulleys on counter-shaft 123 thus varies the speed of counter-shaft 127 and the further driving connections therefrom.

Counter-shaft 127 is connected by a sprocket 129 and chain 130 to a sprocket 131 on a counter-shaft 132, which in turn is connected by a pinion 134 and gear 135 to a shaft 137. At each end, shaft 137 carries sprockets 149 (Figs. 1 and 3) meshing with and driving chains 142 which carry the third paper grippers 80.

Gear 135 on shaft 137 in turn meshes with a gear 150 on the shaft 71, Figs. 1, 2 and 3. Shaft 71 carries a plurality of disks 154 which carry the second grippers 70.

Gear 150 on the second gripper shaft 71 in turn meshes with a gear 160 on a shaft 162 which is the shaft on which the offset cylinder 40 is mounted.

Gear 160 on the offset cylinder shaft in turn meshes with and drives a gear 165 which is fast on the shaft 166 of the main drum. Gear 165 also meshes with and drives several other gears which drive various other mechanisms of the press, as subsequently explained.

The offset cylinder shaft 162 carries at its opposite ends sprockets 170, each of which meshes with and drives an endless chain 180, the two chains 180 carrying the gripper bar 33 on which the gripper fingers 32 are mounted.

The gripper chains 180 at the right end of their path run around sprockets 190, Fig. 3, which are fast on a shaft 191. Referring to Fig. 7, a gear 192 on shaft 191 meshes with a gear 193 on a shaft 194 which carries a cam 195. A slideable member 196 which is forked at one end to extend over the shaft 194 carries a cam follower roller 197, with the result of reciprocating this member 196 as the shaft 194 and cam 195 rotate. The upper end of member 196 is also forked to extend over a pinion 207 on a shaft 206, and is provided with a rack section 208 meshing with pinion 207. The paper stop fingers 30 are mounted on shaft 206, and the train of gearing from shaft 191 to shaft 206 is timed so as to retract the paper stops 30 from the leading edge of the sheet at the moment that the leading edge of the sheet is gripped by the first grippers 32. A torsion spring 206a (Fig. 4) on shaft 206 is adapted to return the shaft 206, paper stop fingers 30 and slideable member 196 to the positions shown in Fig. 7, as permitted by rotation of the cam 195.

Referring again to Fig. 7, the side jogger indicated generally at 31, is adjustable for various widths of sheets, and is also adapted to be set either to jog the sheets to their left or to

their right. In any of its adjustments this mechanism receives its drive through a square shaft 220, Fig. 7, which in turn is driven by sprocket 221, chain 222, sprocket 223, shaft 224 and a gear 225 which meshes with the previously mentioned gear 193.

Side jogger

After the newly fed sheet is stopped by engagement of its forward edge with the paper stop fingers 30, the sheet is aligned with side guides by being jogged either to the left side or right side as desired. The side jogger mechanism indicated generally at 31 includes alternatively useable units at the left and right of the sheet, the two units being similar but oppositely arranged.

Each side jogger unit includes a frame element 240, Figs. 5 and 6, which is laterally adjustable on a stationary guide 241, Fig. 5, lying beneath the level of the paper sheet. Horizontal extensions 242 on the frame carry sleeves 243 which surround and are slidable on the square driving shaft 220, permitting the unit to be adjustably positioned lengthwise of the square shaft and widthwise of the sheets. A lateral edge guide 250 is mounted on the frame element and is finely adjustable laterally of the direction of sheet feed by means of a screw adjustment indicated at 251.

Vertical posts 253 hold a vertically movable slide 254 which is yieldably urged downwardly by springs 255 on the posts 253. A cam 260 is continuously rotated by bevel gearing 261 and 262 from the square shaft 220, and operates a cam follower roller 264 carried by the vertically movable slide 254, so that the operation of the cam 260 and the springs 255 raises and lowers the slide 254 (Fig. 5) on the posts 253.

A further slide 262, laterally movable on the slide 254, carries a depending yoke portion 263 which extends around and engages a crank pin roller 265 extending horizontally from the cam 260. The circularly moving crank pin roller 265 thus acts as a cam to impart horizontal reciprocation to the slide 262.

A presser member 266 extends through a slot in the lateral edge guide 250 and is supported by a post 267 which is vertically adjustable by means of a nut 268 threaded thereto at its upper end. A spring 269 yieldably urges presser member 266 downwardly to the extent permitted by nut 268. Adjustment of the nut 268 permits the presser member 266 to be raised to an inoperative or idle position or to be lowered so that it acts upon the sheets. In Fig. 4 the left jogger unit is shown with its presser member 266 operative and the right jogger unit is shown with its presser member raised to an inoperative level. Fig. 4 thus shows the adjustment employed for jogging the sheets toward the left.

The combined action of the two cam means of the jogger unit is to move the presser member 266 laterally outward while bearing upon the sheet (as in the full line view of the left presser member 266 of Fig. 4) so as to pull the sheet against the lateral edge guide 250, then raise the presser member and move it inwardly at a higher level at which it is out of contact with the sheet (as in the broken line view of the left presser member 266 of Fig. 4), then lower the presser member into contact with the left sheet, and so on. Meanwhile the presser member 266 of the other jogger unit moves idly in a similar path sufficiently above the level of the sheet to

clear the sheet on both the inward and outward strokes.

Beneath the path of travel of the respective presser members 266 of the two units, there are provided two laterally slidable bars 270 each yieldingly urged toward the middle of the sheet by a spring 271 which connects these two bars. Each bar 270 is provided with an upstanding bracket 272 carrying a roller 273 adapted to engage the outside edge of the yoke 263. Consequently, when the presser member moves outwardly in contact with the paper, the paper is supported from beneath by a similarly moving bar 270, thus obviating any risk of the paper failing to move outwardly into contact with the lateral edge guide 250 while at the same time permitting use of a very light grip of the presser member upon the paper.

Each bracket 272 is laterally slidable on its bar 270 and the bracket which cooperates with the active jogger unit is coupled to its bar 270 by tightening a set screw 272a. The bracket 272 which is associated with the inactive jogger unit is uncoupled from its bar 270 by loosening its set screw, and this bracket may if desired be shifted out of range of the corresponding yoke 263. The right-hand bracket 272 is omitted from Fig. 4 because the right-hand jogger unit is in its inactive adjustment. The slidable bar 270 of the active jogger unit moves back to its innermost position against a suitable stop as the raised presser member 266 returns to position to engage the next sheet.

Upon alignment of a lateral edge of the sheet 35 with the lateral edge guide 250 the sheet is in position to be engaged by the sheet-carrying grippers now to be described.

As will be apparent from the driving connections previously described, the paper stop fingers 30 are operated in synchronism with the side jogger and with the sheet-carrying grippers and hold the sheet against forward progress during the side jogging and until the first grippers close upon the sheet.

First conveyor and grippers

As previously described, a gripper bar 33 provided with gripper fingers 32 is carried by chains 180 which run on sprockets 170 on the shaft 162 of the offset cylinder and on sprockets 190 on the shaft 191. The gripper bar 33 is of wedge-shaped cross-section (indicated in Figs. 1 and 9) near its two ends, and outwardly of the wedge-shaped cross-section and symmetrically therewith is attached to one of the links of each chain (Fig. 8) so as to follow generally the traveling and turning movements of the chain.

The wedge-shaped portions of the gripper bar fit accurately into corresponding wedge-shaped openings 300a in a pair of disks 300 mounted on the offset cylinder shaft 162 and in similar corresponding openings in a pair of disks 301 mounted on the shaft 191. Thus notwithstanding any slight slack which may develop in the chains 180, the gripper bar 33 and the forward edge of the sheet carried thereby will always be accurately registered with the surface of the offset cylinder 40. Moreover the gripper bar, through its engagement with the wedge-shaped recesses in disks 301, will always occupy a predetermined position at the instant of retraction of the paper stop fingers 30 and closure of the gripper fingers 32, so that the forward edges of sheets fed to the gripper bar will occupy a predetermined place on the gripper bar and hence,

subsequently, on the offset cylinder 40. Accurate timing of the retraction of the paper stops with respect to the location of the gripper bar and closure of the gripper fingers is assured by the close mechanical connection (Fig. 7) between shaft 191 which carries the recessed disks 301 and the shaft 206 which carries the paper stop fingers 30.

It will be observed from the relative positions of the axes of shafts 191, 162 and 166 in Fig. 1 that the line of travel of a sheet carried by gripper bar 33 becomes tangent to offset cylinder 40 and disks 300 a substantial distance ahead of the line intersecting the axes of offset cylinder 40 and main cylinder 42, so that the gripper bar 33 which carries the sheet is well settled in the wedge-shaped notches 300^a of disks 300 before the sheet becomes squeezed between the offset cylinder and the impression segment of the main cylinder.

As indicated at Fig. 8 the gripper bar 33 throughout most of its length is cut away to receive a shaft 304 upon which the gripper fingers 32 are individually clamped by clamping nuts 304^a. Coil springs 305 of which one is shown in Fig. 8 yieldingly urge the shaft 304 to carry the gripper fingers 32 to their closed positions in which their trailing ends engage with the gripper bar.

A small diameter pinion 306 carried at the end of shaft 304 meshes with an internally toothed rack segment 307 which is pivotally mounted on the gripper bar end at 308. Rack segment 307 is provided with a crank arm 309 integral therewith, carrying a cam follower roller 310 adapted to engage stationary cams to swing the rack and hence turn the pinion 306 to hold the gripper fingers temporarily open.

As shown in Figs. 3 and 9 the machine is provided with one such cam 311 partially surrounding the shaft 191, this cam being adapted to open the gripper fingers, hold them open for an instant as the gripper bar approaches the paper stop fingers 33, and then allow the gripper fingers quickly to close upon the forward edge of the sheet. In Fig. 9 the cam follower roller 310 is shown as just having dropped off from the high part of the cam 311 and allowed the fingers 32 to close. Also, as indicated in Fig. 3 the machine is provided with another such cam 312 surrounding the shaft 162 of the offset cylinder. In Fig. 3 the gripper bar is shown at the point of transfer of the sheet, and the cam follower roller 310 is about to engage the high part of the cam 312 to open the gripper fingers.

The construction of the mechanism for controlling the fingers, comprising the pinion 306 and the internally toothed rack 307 provides a very compact mechanism carried by the gripper bar and capable of imparting a quick opening and closing movement to the fingers. This is especially advantageous in the closing of the fingers at the point of reception of the paper. The gripper bar comes into position beneath the leading edge of the sheet with its gripper fingers open to approximately the extent shown in Fig. 10^a, and the closing movement of the gripper fingers, to the position of Fig. 10, amounts to approximately 180°.

As indicated above, in the normal or closed position of the gripper fingers 32 they are urged to this closed position by the coil springs 35. The resiliency of grip of the fingers on the paper is further increased by the fact that the fingers themselves are of resilient spring steel and are

of reduced thickness throughout most of their length as shown at 32^a in Fig. 10.

It will be observed that whereas in my prior Patent No. 2,257,490 the chains carrying the paper to the offset cylinder also carried the paper away from the offset cylinder and hence needed to be provided with a plurality of gripper bars, the press described herein employs chains 180 which carry the paper no farther than the offset cylinder and hence require only a single gripper bar. This feature is of considerable advantage since in the press described herein each sheet is carried to the offset cylinder by the same gripper bar and there is thus no possibility of any difference in registry of alternate or successive sheets with the offset cylinder.

Pressure mechanism and control of pressure mechanism in accordance with sheet feed

As shown in Figs. 11 and 12 the shaft 162 of the offset cylinder is mounted in sliding blocks 325 which are vertically movable in guideways 326. A pressure control or cam shaft 328 is eccentrically mounted at 329 at its ends and acts as a cam, through adjustable tappets 328^a, to support the sliding blocks 325. Rotation of the control shaft 328 in a counterclockwise direction as viewed in Figs. 11 and 12 permits the offset cylinder to move away from the main cylinder, and rotation of the control shaft 328 in a clockwise direction lifts the offset cylinder and forces it under pressure against the main cylinder.

A sliding collar 330 (Fig. 13) on shaft 328 carries a horizontal connecting pin 331 which is guided through a slot in an arm 332^a which extends from a fixed collar 332 on shaft 328. Connecting pin 331 is adapted to be projected to the right in Fig. 13 to a position in which it underlies a shoulder 334 on a vertically reciprocable pressure fork or plunger 335.

A cam follower roller 336 (Figs. 11 and 12) on the pressure fork 335 is adapted to be contacted by cam surface 338 of a cam 339 mounted on the shaft 166 of the main cylinder, to apply pressure to the pressure fork or plunger 335 at each rotation of the main cylinder.

The connecting pin 331 is urged to the left in Fig. 13 by a spring 340 which acts on the slidable collar 330, tending to disengage the pin 331 from the pressure fork shoulder 334, thus allowing the pressure fork or plunger 335 to move idly.

A solenoid 342 (Fig. 12) has its movable armature 343 connected by a flexible cable 344 to the slidable collar 330. Energization of the solenoid 342 by means of a push-button switch 342^a (Fig. 37) thus pulls the pin 331 to the right in Fig. 13, carrying it into the path of the pressure fork shoulder 334.

During continued printing, the pressure of pressure fork shoulder 334 upon the pin 331 retains the pin under this shoulder against the action of the spring 340, thus keeping the pressure fork connected to the pressure control eccentric shaft 328 as long as the pressure fork is sufficiently low in position for the shoulder 334 to bear against the pin 331.

The shape of the cam 339 on the main cylinder shaft is such that the high part of the cam surface 338 bears against cam follower roller 336 only during the presentation of the plate segment 43 to the offset cylinder.

In normal printing, pressure between the offset cylinder and the impression segment 44 is secured by latching the pressure fork in a pres-

sure-applying position by detector-controlled latch mechanism.

A latch 350, Fig. 14, is slidably mounted in a block 351 and includes a bevelled portion 352 adapted to slide into a wedge shaped recess 353 in the pressure fork 325. Latch 350 is normally urged to the right or unlatched position in Fig. 14 by a spring 355, but upon the detection of feed of a sheet to the press, latch 350 is urged to the left and into the recess 353 by a bell crank 357 which is connected by a flexible connection 358 to the movable armature 359 of a solenoid 360 as shown in Fig. 11.

Solenoid 360 is energized by the interruption of a light beam by a sheet as the sheet is carried toward the offset cylinder by the gripper fingers 32 and gripper bar 33.

In Fig. 11 a source of light such as an electric lamp is indicated at 370 and a photo-electric cell normally exposed to the light beam is indicated at 371, the beam of light from lamp 370 to cell 371 being adapted to be interrupted by a properly fed sheet carried by the gripper bar 33 passing along the upper run of chain 180.

Referring to the wiring diagram of Fig. 37, solenoid 360 is normally de-energized and is adapted to receive its operating current through a circuit which includes the terminals D and F of a relay 380 which is de-energized when the photo-electric cell 371 receives light from the light source 370. When the beam from the light source 370 to the cell 371 is interrupted, the relay 380 is energized, closing the circuit between terminals D and F and sending an impulse through the circuit which includes the solenoid 360.

This energization of relay 380, and consequently of the solenoid 360, takes place during the offsetting portion of the cycle, that is, while the image from the lithographic plate on segment 43 is being transferred to the offset cylinder, and hence while the pressure fork 325 is held in its depressed position of Fig. 14 by the high surface 338 of the cam 339. The notch 353 is accordingly in position to receive the latch 350.

The block 351 which carries the latch 350 is vertically slidably mounted in a stationary guide bracket 383 (Fig. 13) and a screw 384 which is rotatable in the bracket 383 is threaded into the block 351. A rod consisting of jointed portions 385, 386 and 387 (Figs. 13 and 11), fastened to the screw 384 and to a knob 389, enables the screw 384 to be turned to adjust the level of the block 351 and hence the level at which the latch 350 will hold the pressure fork during proper presentation of a sheet between the offset cylinder and impression segment. Normally the latch-carrying block 351 will be adjusted at such level that the latch 350 will have at least a slight clearance from the bottom surface of notch 353 as the latch enters the notch during the offsetting portion of the cycle.

When a properly fed sheet passes and interrupts the light beam at a time near the end of the offsetting portion of the cycle, the solenoid 360 inserts the latch in the notch 353 and holds it there until the latch is caught and held by the bottom surface of the notch when the cam surface 338 ceases to apply downward pressure to the pressure fork. When the trailing end of the sheet subsequently passes the light beam, the solenoid 360 becomes deenergized.

If a sheet fails to be fed, the solenoid 360 will be energized as a result of interruption of the light beam by the passing empty gripper bar, but

will become de-energized while the cam surface 338 is still applying downward pressure to hold the pressure fork in its lowest position. The latch then is removed from the notch by the spring 355 while the cam surface 338 is still active, and at the end of the offsetting portion of the cycle the pressure fork is not latched but is free to rise considerably higher than if it were latched. The resulting considerable rise of the pressure fork permits a considerable counter-clockwise movement of the shaft 328 which allows the offset cylinder to drop out of position to press against the plate segment of the main cylinder, preventing the offsetting of a further image onto the offset cylinder.

Moreover, when the pressure fork fails to be latched by the latch 350, the shoulder 334 of the pressure fork will move higher than will the connecting pin 331, breaking the normal frictional contact between these parts, whereupon the spring 340, Fig. 13, will pull the pin 331 out from under the shoulder 334. Succeeding strokes of the pressure fork will thereupon be idle and the offset cylinder will remain out of contact with the main cylinder until the solenoid 342 is reenergized by manual operation of the switch 342a.

It will be observed that in the normal operation of the press, while sheets are being normally fed, the pressure fork or plunger 335 moves only through so much of its stroke as effects the relatively slight separation and approach of the axes of the offset cylinder and the main cylinder appropriate to the successive presentation of the plate segment and impression segment to the offset cylinder.

Location of the light beam

40 Interruption of the light beam B from the lamp 370 to the photoelectric cell 371 by the gripper bar 33 as the latter travels along the lower run of the chains 180 can be avoided by disposing the light beam so that it is not crossed by the gripper bar in this lower run of the chains. This may best be accomplished by locating the lamp 370 and cell 371 as indicated diagrammatically in Figs. 3 and 3a, with both the lamp and cell outside of the courses of the chains 180, but with one of these elements, for instance the lamp, somewhat above the other of these elements in such manner that the beam B crosses the line of travel of the gripper bar only at the upper run of the chains 180.

45 The control of various parts of the press, and more especially the latch solenoid 360, by the interruption of the light beam B by the sheet 50 being fed, involves certain further relations of the light beam to the press which may be summarized as follows:

The light beam is in a position such that the sheet being fed interrupts the beam while the lithographic plate segment 43 of the main cylinder is active, during the time the latch 350 is neither held in latching position by the pressure fork 325 nor held out of latching position by the pressure fork 325. As indicated above, during the presentation of the plate segment to the offset cylinder the notch 353 in the pressure fork is located so as to permit free movement of the latch 350 into or out of latching position.

55 The point of interruption of the light beam by the paper is sufficiently near to the line of printing contact between the main and offset cylinders to permit relatively short sheets to reach the line of printing contact and be gripped 70 between the main and offset cylinders before the

light beam is re-established after passage of the sheet and the latch solenoid 350 accordingly de-energized.

The point of interruption of the light beam by the paper is however sufficiently spaced from the line of printing contact so that the interrupting effect of an empty gripper bar does not persist up to the time that the impression segment becomes active, but on the contrary the beam is re-established and the latch solenoid 360 is de-energized in time to let the latch 350 move out of the notch 353 before the impression segment is presented to the offset cylinder.

These conditions are best provided for in the press herein shown by locating the light beam B so that it is approximately 4" from the line of printing contact between the main and offset cylinders at the point where the beam is interrupted by the paper.

Limit switches responsive to application of pressure to offset cylinder

Numerous operations of the machine are controlled by a limit switch indicated at 390 in Fig. 12 which preferably constitutes a single throw gang switch comprising switches 390^a, 390^b and 390^c, which control various circuits as shown by the wiring diagrams of Figs. 37 and 37^a. The limit switch 390, including its three component switches, is responsive to the application of pressure to the offset cylinder, normally tending to open, but being closed whenever the offset cylinder is held up in position to press against the main cylinder. Since, as indicated above, the pressure of the offset cylinder is released when failure of feed is detected, the various operations of the machine which are controlled by the switches 390^a, 390^b and 390^c are also controlled by the detection of failure of feed. It should be explained here that the employment of three limit switches 390^a, 390^b and 390^c rather than a smaller number of such switches, is described herein in the interest of simplicity. All three of these limit switches act simultaneously in response to the release and application of pressure at the offset cylinder. The skilled electrician will be able to cause a lesser number of limit switches to exercise the same controlling functions by utilizing more complicated, or apparently more complicated, control circuits.

A vertically movable rod 394 is pivotally connected to an arm 392^a constituting a projection from collar 332, and rod 394 has fastened thereto near its bottom end a bracket 395 adapted to depress a cam follower roller 396 on an operating arm 397 of the limit switch 390. The adjustment of the switch and rod 394 is such that in the pressure applying positions of the offset cylinder the limit switch 390 is closed. A spring 398 may be provided to assist the upward return of rod 394 and bracket 395 upon release of the latch 350.

Prevention of latching of pressure fork while pressure fork is disconnected from offset cylinder

As indicated above, the several switches which comprise the gang limit switch 390 control several of the operations of the press. Switch 390^a, when open as indicated in Fig. 37 as in the event of disconnection of the pressure fork and offset cylinder, breaks the circuit through the latch solenoid 360. This renders the latch 350 incapable of moving to latching position until the offset cylinder has first been connected to the pres-

sure fork by means of the pin 331 by manual operation of the push-button switch 342^a, and the offset cylinder brought again into pressure relation to the main cylinder.

Thus it is assured that the pressure fork, while disconnected from the offset cylinder, will be capable of rising during each revolution of cam 339 sufficiently high so that it is possible to project the pin 331 into the path of this shoulder 334 for reconnection of the pressure fork and offset cylinder.

Second or transfer conveyor and grippers

It has been mentioned above that it is desirable for the chains 180 that carry the gripper bar 33 and first grippers to carry the paper no farther than the offset cylinder and to carry only a single gripper bar so that all of the sheets can be carried to the offset cylinder by the same set of grippers. It is also an advantage to deliver the printed sheets in a pile with the side of the sheet that has received an image from the offset cylinder uppermost.

With these objects in view the machine is provided with a set of second or transfer grippers adapted to transfer the sheets at the offset cylinder from the first grippers to a third or delivery set of grippers. The transfer grippers indicated generally at 70 are respectively mounted upon disks 154 that are fast on the previously mentioned shaft 71, Figs. 1 and 17. Figs. 3 and 15 show the transfer grippers 70 in the act of receiving the sheet from the first grippers 32 and Fig. 16 shows the transfer grippers as having moved approximately 90° around the shaft 71 and in the act of delivering the sheet to the delivery grippers 80.

It is an object of the invention to construct the second or transfer grippers so that they can enter into relatively small recesses in the gripper bar 33 as the latter lies in the recess of the offset cylinder. It is, of course, further necessary that this second set of grippers should close quickly upon the forward edges of the sheets presented by the first set of grippers at the point of tangency of the paths of these two sets of grippers. The second set of grippers is accordingly constructed to operate in a different manner from ordinary grippers and more particularly to close upon the sheet by movement about an axis perpendicular to the sheet instead of about an axis parallel to the sheet.

Each gripper 70 of the second set of grippers is shown as including a bracket 406, Figs. 17, 19 and 21, fastened to one of the disks 154 and including as an integral part a relatively stationary jaw or anvil 407 adapted to engage the sheet. The gripper also includes a movable jaw 410 which projects transversely from a rotatable element 411 contained within the bracket 406, the axis of rotation of element 411 and of movable jaw 410 being approximately perpendicular to the paper and its path of travel. Fig. 21 shows the movable gripper jaw 410 in full lines in its open position, and in broken lines in its closed position overlying the stationary jaw 407. In its rotation from the open to the closed position the jaw 410 is further given a slight movement in the direction of the axis of the rotatable member 411 to cause it to approach toward the plane of the fixed jaw 407. The combined rotating and axial movement of the movable jaw 410 thus amounts to a helical movement.

A preferred means for imparting this helical movement includes a helical groove 415 developed

in the surface of the rotatable member 411, and a holding member in the form of a ball 416 positioned in helical groove 415 by a threaded pin 417. The inner end of the rotatable member 411 of each of the second grippers is provided with a pinion 418 and the several grippers are rotated through their pinions by a rack 420 movable at right angles to the several disks 154. A stationary cam 425 surrounding the shaft 71 engages a cam follower roll 426 on a bell crank 427, the bell crank engaging a collar 422 on the rack 420 to shift the rack and rotate the grippers. A tension spring 429, connecting the rack to one of the disks 154, yieldingly urges the rack to the left in Fig. 17 in opposition to the action of cam 425, urging the rack to close the gripper jaws.

The rack 420 is provided adjacent to its ends with portions 420^a of rounded section at each of which the rack is slidably mounted in a sleeve 420^b (Fig. 17) which extends through a supporting disk 420^c on shaft 71. A threaded portion 420^d carries a stop nut 420^e which may be adjusted to abut against the end of sleeve 420^b to limit the left or jaw-closing movement of rack 420.

In Fig. 15 in which the second grippers 70 have just closed upon the sheet at the offset cylinder, it will be observed that the second gripper jaws 410 are enabled to enter into a relatively small recess in the first gripper bar 33 and do not require any enlargement of the opening or gap in the offset cylinder 40 beyond that which receives the first gripper bar.

Simultaneously with the engagement of the sheet by third grippers carried by a delivery chain 142 (Fig. 16) the rack 420 operates to open the second gripper jaws 410 and carry them beyond the forward edge of the sheet.

Third or delivery conveyor and grippers

As indicated above, the delivery conveyor comprising the chains 142 carries two sets of third grippers, indicated generally at 80 which alternately receive sheets from the second or transfer grippers 70.

Referring to Figs. 16, 22, 23 and 24 each set of grippers includes a gripper bar 146 attached at opposite ends to pivots of the chains 142, the bar 146 having a central portion 146^a of narrow section on which raised portions 146^b (Fig. 24) serve as stationary jaws for the plurality of movable gripper jaws. A shaft 441 extending from end to end of the gripper bar and mounted in brackets 442 carries movable jaw members 445 freely rotatable thereon. Each movable jaw member 445 is forked in the region of the shaft 440, and an operating lever 447, fast on shaft 441, is received between the two branches of each movable jaw member 445. A spring 448 is interposed between the operating lever 447 and a tail piece 445^a which is integral with the movable jaw 445, and spring 448 thus connects the operating lever and movable jaw so that rotation of the shaft 441 clockwise in Fig. 24 acts through the lever 447, spring 448 and tail piece 445^a to move the jaw 445 yieldingly toward engagement with the stationary jaw 146^b. Rotation of the shaft 440 counterclockwise causes the operating lever 447 to engage a pin 449 (Fig. 24) secured to the movable jaw member 445 and consequently elevate the jaw positively to an open position.

The shaft 441 is yieldingly urged in clockwise direction as viewed in Fig. 24 by a spring 450, Fig. 22. A crank arm 453 at an end of the shaft 441 carries a cam follower roller 454 adapted to

engage a plurality of stationary cams to retain the gripper jaws temporarily open. One such stationary cam is shown in Fig. 3 at 456 surrounding the shaft 137 and adapted to present the third grippers to the second grippers in open condition and then close at the position of Fig. 16. Another such cam is shown in Fig. 3 at 457 located adjacent to the lower horizontal run of chain 142 and adapted to open the third grippers and retain them open a short time while the sheet is being discharged from the third grippers onto a pile.

The discharge of the sheets from the third grippers, accomplished at the lower run of the generally triangular course of the chains 142, drops the sheets onto the pile with their sides which have received an image from the offset cylinder uppermost.

Further printing of sheets as they are carried away from offset cylinder; numbering mechanism

One of the advantages of the arrangement of the delivery chains 142 in combination with the other parts of the press is in facilitating incorporation in the press of a conveniently accessible mechanism adapted further to print the sheets on their sides that have received a printed image from the offset cylinder. In the preferred form of the invention as illustrated in the drawings such further printing mechanism comprises a numbering mechanism, although various other forms of printing mechanisms can also be employed.

Referring to Figs. 3 and 25 a shaft 478, carrying sprockets 479 which mesh with the chains 142, carries a plurality of laterally adjustable hubs 481 to each of which one or more serial numbering units indicated generally at 90 may be detachably secured. These numbering units are diagrammatically shown as the well-known Wetter numbering units, each including an actuating arm 482 carrying a cam follower roller 483. A stationary cam 484 is positioned in the path of the actuating arm of the one or more numbering units on each hub 481 so as to actuate the arm 482 once upon each rotation of the numbering unit. The numbering units rotate at substantially the speed of the sheets carried by the third or delivery conveyor.

The numbering units are preferably set to advance their printing numbers one digit for each two times that the actuating arm 482 is tripped by the stationary cam 484. Each numbering unit 90 will be brought to the plane of the sheet carried by chains 142 once during the passage of the sheet and again in the interval between the passage of successive sheets. Thus when set to advance its printing numbers one digit for each two contacts with the stationary cam 484, each numbering unit will number successive sheets with successive numbers.

With, for example, two numbering units 90 spaced at any desired distance circumferentially of a single hub 481, each sheet will be numbered twice, once by each of the two units, at two longitudinally spaced points. With, for example, two numbering units 90 respectively mounted on two axially spaced hubs 481 on the shaft 478, each sheet will be numbered twice, once by each unit, at two laterally spaced points. More or fewer numbering units can be applied as desired.

Suitable inking mechanism for the numbering unit or units may include an ink fountain 490, Fig. 3, provided with an ink delivery roll 491

rotated by a ratchet wheel 492 which is driven by pawl 493 and bell crank 494 from an eccentric 495 driven by the sprocket shaft 476. The inking mechanism may also include a distributor roll 500 adapted to run in contact with the type of the numbering units, and a suitable ductor roll 501 for carrying ink from the delivery roll 491 to the distributor roll 500. As diagrammatically indicated in Fig. 3, the ductor roll 501 is carried by crank arms 503 which are pivotally mounted at 504 and which are oscillated by contact of a cam follower roll 506 with a rotary cam 507 which is driven by a chain, including a chain 507, from shaft 475.

Referring to Figs. 3, 26, 27 and 28 a shaft 510 forms a pivot for arms 511 and a tie bar 512 connecting these arms, and the pivoted assemblage of the arms 511 and tie bar 512 form the support for a numbering unit platen roll shaft 514 which is rotatably mounted therein. Longitudinally adjustable rubber platen rolls 518 are provided on the shaft 514 and can be shifted lengthwise of the shaft 514 to bring them into position to co-operate with the numbering unit or units provided on the axially adjustable hubs 481.

A suitable drive for the platen roll shaft 514 may include as shown in Figs. 26 and 27 the sprocket shaft 475, a gear 520, a rotatable stud (Fig. 25), indicated generally at 521 and further described later, which includes a gear 522 and a sprocket 523, a chain 524, a double sprocket sleeve 525 coaxial with the pivot shaft 510, a chain 527 and a sprocket 528 on the platen roll shaft 514. The arrangement of this drive is to rotate the one or more platen rolls 518 at the same surface speed as the passing paper and the passing numbering unit or units.

The numbering unit platen rolls are held out of printing contact with the numbering unit or units during the gap between successive sheets carried by the third grippers. As indicated in Figs. 3, 26 and 27 a crank arm 530 which is secured to one of the arms 511 of the platen roll assemblage carries a cam follower roller 531 running in contact with a rotary cam 532 which is a part of and rotates with the stud 521 previously described. Contact of the high part of the cam 532 with the follower roller 531 swings the arms 511, tie bar 512 and platen roll shaft 514 about the axis of shaft 510 to hold the platen rolls 518 out of contact with the inking units. The train of intermeshing gears 520 and 522 by which cam 532 is driven from sprocket shaft 475 is such that the cam 532 makes one revolution for each gripper bar 146 that passes the platen roll or rolls 518, and the shape of cam 532 is such that the platen rolls 518 will clear the passing gripper bar, then descend into contact with the sheet and remain in that position during passage of a length of chain equal to approximately half the distance between successive gripper bars, then move away from the plane of the sheet. As a result the numbering unit is prevented from printing onto the platen roll in the gap between successive normally fed sheets.

During passage of the sheet down the inclined path of travel past the numbering unit or units the sheet is further supported from beneath by a plurality of disks 535, Fig. 25, which are adjustable lengthwise on shaft 478. Each of these disks is cut away at 536 to clear the passing gripper bars.

During passage of the sheet around the curve from the inclined part of its path to the horizontal lower part of its path, the sheet is further

guided by disks 537 which are cut away, similarly to disks 535, to clear the gripper bars.

Control of numbering mechanism in accordance with sheet feed and pressure at offset cylinder

- 5 The numbering units are prevented from printing onto the platen roll during continued running of the machine after a sheet has failed to be fed in the normal manner.
- 10 Referring to Fig. 28, one of the arms 511 of the pivoted platen roll assemblage carries a solenoid 540 of which the movable armature member 541 is guided in a slideway 542. A collar 545 on shaft 510 and suitably held against rotation is notched at 547 so that when the arm 511 is moved out away from the numbering unit the movable armature member 541, excepting when retracted by energization of the solenoid 540, can drop down into the notch 547 and lock the arm 511 against return movement toward the numbering unit, that is, against movement in a clockwise direction as viewed in Fig. 28.

- 25 Solenoid 540 is ordinarily energized during normal operation of the press. As previously explained, when a sheet fails to be fed to the main and offset cylinders, non-detection of such sheet by the photo-electric cell results in unlatching the pressure fork, separation of the main and offset cylinders, and consequent opening of the limit switch 390^a. Such opening of limit switch 390^b deenergizes the solenoid 540, thus permitting the movable armature 511 to prevent movement of the platen roll assemblage into printing position.
- 30 A manually controlled switch 540^a, in series with solenoid 540, is normally closed but may be opened to prevent this solenoid from being energized, as for instance when it is desired to operate the press without operating the numbering mechanism.

Pile delivery

- 45 As the sheets are discharged from the gripper bars 146 of the delivery conveyor the sheets drop printed side up upon a stack 100 supported on a table indicated diagrammatically at 101, Fig. 2, and slide vertically on slides 578.

- 50 A suitable mechanism for lowering the table 100 as the paper accumulates thereon may comprise chains 579 shown in Fig. 2 adapted to be raised or lowered by corresponding sprockets 580. Each sprocket 580 is fast on a shaft 581 which also carries a worm gear 582 meshing with a worm 583 on a shaft 584. A ratchet wheel 586 on shaft 584 is adapted to be engaged by a ratchet pawl 590 pivotally mounted on a bell crank 592, and bell crank 592 is continuously oscillated by an eccentric 593 on shaft 475, a cam follower 594, yoke 595 and a connecting link 596.

- 60 The ratchet pawl 590 includes a tail portion 597 carrying a cam follower roller 598. A curved cam plate 600 is mounted on the vertically movable armature 601 of a solenoid 602 above the path of cam follower roller 598. When the solenoid 602 is not energized the curved cam plate 600 depresses the cam follower roller 598 and tail 597 of the pawl 590, so as to retain the pawl out of engagement with the ratchet wheel 586, thus allowing the pawl to swing idly. On the other hand when solenoid 602 is energized as described hereinafter cam plate 600 is lifted sufficiently to allow the pawl 590 to drop into engagement with the teeth of the ratchet wheel 586 as shown in Fig. 2. When in this position the pawl and ratchet wheel cooperate to turn the worm 584

and parts driven thereby, to lower the stack table 101. De-energization of the solenoid 602 immediately stops the lowering of the stack table.

Control of pile delivery; detection of stack elevation in feeder

Figs. 29 and 30 are fragmentary views of the feeding apparatus of the press, which preferably is constructed as described in my copending application Serial No. 590,225, filed April 25, 1945, matured into Patent No. 2,497,849, February 21, 1950, which may be referred to for a more detailed description. Fig. 30 shows a fragment of the continuously rotating axle 26, roller 28^a and one of the sprocket-driven conveyor chains 38 carrying sets of cords 18^a which convey the sheets from the stack 12 of Fig. 29 into the press. Fig. 29 shows a stack 12, of sheets to be printed, carried by a table 13 supported by bracket 85 which is slideably mounted on guide bars 89.

Sheets are lifted singly and in succession from top of stack 12 by reciprocating suction picker nozzles 56 which move downwardly and upwardly through gaps between successive sets of the cords 18^a, picking up the trailing end portion of the top sheet, lifting this trailing end portion above the path of travel of the next set of cords 18^a, and holding it there until such set of cords 18^a complete the separation of the sheet from the stack. The suction in the nozzles 56 is then broken and the traveling cords 18^a advance the sheet into the press.

Lifting of the sheets is facilitated by intermittent blasts of air directed against the upper right face of the stack of Fig. 29 by air blast nozzles 140, such blasts of air fanning out the top several sheets of the stack and accomplishing the first part of the elevation of the trailing edge portion of the top sheet.

Suction is supplied to the nozzles 56 through flexible tubes 83 (Figs. 29 and 37^a), a suction header conduit 75^c, conduits 75^b and 75^a, and a mechanically controlled valve 14 which breaks the suction at the proper times, a conduit 73, and a flexible coupling 73^a which leads to the suction side of a motor-driven air pump indicated diagrammatically at 1060. Air is supplied under pressure to the nozzles 140 from the pressure side of the pump 1060 (Fig. 37^a) under the control of a mechanically actuated piston valve 161.

Table 13 is adapted to be elevated by a chain 85^a driven by sprocket 85^b on a shaft 95 which is rotated by a worm gear 96. A worm 97, adapted to drive the worm gear 96, is carried on a shaft 98 which also carries a ratchet wheel 200. An eccentrically weighted plate 201 is freely rotatable on shaft 98 and carries a pivotally mounted pawl 202 adapted to fall by gravity into engagement with the teeth of ratchet wheel 200. The center of gravity of the plate 201 is toward the right of the shaft 98 as seen in Fig. 29, which causes the plate 201 to tend to rotate about the shaft 98 in a clockwise direction, tending to keep a pin 203, carried by plate 201, in engagement with the upper end of a slot 204 in a pitman 205. The lower end of this pitman is pivotally connected to an eccentric pin 205^a on a continuously driven shaft 78.

A paper stack height feeler roller 15 is carried by the upper end of a member 88 and bears upon the topmost sheet of the stack. Member 88 is pivotally connected to the inner arm of a double crank 88^a of which the outer arm is pivotally connected to the lower end of a connecting rod 88^b. Rod 88^b carries a slotted head 209 which

slidably engages a pin 210 at the right end of a lever 211 which is pivotally mounted on a stud 212 projecting from a side frame plate of the feeder. The end of the lever 211 opposite to the pin 210 is adapted to detain a shoulder 201^a (Fig. 30) which is integral with plate 201, thus preventing the plate from rotating counterclockwise, as viewed in Figure 29. As the height of the top of the stack 12 decreases, the control feeler 5 roller 15 and member 88 descend, the crank 206 rotates, the connecting rod 88^b descends and the detent lever 211 disengages the shoulder 201^a and allows the plate 201 to rotate counterclockwise, as viewed in Figure 29, bringing the pawl 10 202 into position to engage a new tooth or teeth on the ratchet-wheel 200. Operation of the pitman 205 then results in actuating the pawl 202 to turn the ratchet-wheel 200, shaft 98, and shaft 95 and move the chain 85^a to lift the table 13 and thereby raise the top of the stack to the appropriate level for feeding from the top of the stack. A handwheel 98^a may be provided on shaft 98 for adjusting the paper stack table and also for lowering it to receive a further supply of sheets.

A limit switch 610, not provided in the said copending application, is located on the feeder so that its operating arm 610^a is adapted to be cammed to the right in Fig. 29 by rotation of the plate 201 in a clockwise direction, and the limit switch 610 is so arranged that such movement of its arm closes the switch, closing a circuit through the solenoid 602 of the pile delivery control mechanism.

Thus each time the table 13 of the feeder is elevated by the mechanism of Figs. 29 and 30, the table 101 (Fig. 2) at the delivery end of the press is correspondingly lowered.

It is often convenient, especially in starting the 40 press, to run the press idly without feeding paper through it and in this operation the feeder paper stack table 13 may either be empty or the top of the stack 12 may be sufficiently low so that it does not engage the feeler 15, and consequently 45 during such running the table 13 may be caused to rise. In such idle running of the press, the limit switch 390^b will be open because of the absence of pressure at the offset cylinder, and because this limit switch 390^b is interposed in 50 the circuit of pile delivery control solenoid 602 (Fig. 37) the latter will not be energized. Accordingly, when the press is run idly, the pile delivery table 101 will not automatically lower even though the feeder paper stack table 13 rises.

55 A manually operated switch 611 is also interposed in the circuit of the pile delivery control solenoid 602 and by opening this switch, automatic lowering of the pile delivery table can be suspended both during idle running and during 60 printing.

Corner jogger

As each printed sheet is deposited on the stack 100, the sheet is aligned with the stack by pairs of corner abutments that respectively approach 65 two adjacent corners of the stack, each diagonally of the top sheet.

In Figs. 31 and 33 the pairs of corner abutments are shown in the position in which they have brought the top sheet into alignment with the 70 stack, abutments 700 and 700 being in contact with the two lateral sides of the stack and abutments 701 and 701 being in contact with the forward side of the stack. In Fig. 32 one pair of corner abutments are shown in their retracted 75 positions, away from the stack, preparatory to

the discharge of a sheet onto the stack by the third grippers.

A preferred system of linkage for causing the diagonal approach and retraction of the abutments with respect to the stack will now be described.

An extensible member indicated generally by the reference character 704 comprises rod portions 705 and 706 each of which carries a pair of abutments 700 and 701, and a sleeve 707 which is secured to rod portion 705 and provides a slidable but non-rotatable connection between rod portions 705 and 706.

The extensible member 704 as shown in Fig. 31 is mounted at its ends in sleeves 709 which are longitudinally adjustable on parallel bars 711. Each bar 711 is pivotally connected to links 712 and 713 which in turn are pivotally connected at 714 and 715 to stationary brackets 716 and 717 which extend from the side frame members 25 of the press.

Shaft 475 carries two identical eccentric cams 719, of which one is shown in Fig. 33, each actuating a cam follower roller 720 on the upper end of a pivoted lever 721. A connecting link 723 connects the bottom end of each lever 721 and the adjacent longitudinal bar 711. Thus the continuous rotation of shaft 475 swings each bar 711 about its points of pivotal support 714 and 715 with a compound motion which has a component lengthwise of the sheets of the stack and also a component transversely of the sheets, toward the other bar 711. Springs 725 restore the bars 711 to the position of Fig. 32, as permitted by the rotation of the cams 719. As the compound motion of the side supporting bars 711, 711 carries them toward the sides of the stack the extensible member 704 connecting the bars 711, 711 contracts, the rod members 705 and 706 approaching each other, and as the compound motion of the side supporting bars 711, 711 carries them away from the sides of the stack the extensible connecting member 704 extends, the rod members 705 and 706 moving away from each other.

Thus at each discharge of a sheet onto the stack the sheet is aligned with the stack by a pair of abutments 700 and 701 which approach the sheet diagonally from one corner and by a further pair of abutments 700 and 701 which approach the sheet diagonally from the adjacent corner, whereupon the pairs of abutments retract in readiness for the discharge of the next printed sheet.

Each side abutment 700 is adjustable lengthwise of its supporting rod 705 or 706, and is mounted thereon by a bracket 700a which is slideable on the rod 705 or 706 and may be fixed in position on the rod by a set screw 700b engageable in a slot 700c in the rod.

Each end abutment 701 is supported by a bracket 701a (Fig. 33a) which is pivotally secured to the bracket 700a of the neighboring side abutment by a bolt 701b. A strong compression spring 701c interposed between brackets 700a and 701a normally frictionally prevents the bracket 701a and end abutment 701 from swinging from their operative positions as shown in Fig. 31 and as also shown in full lines in Fig. 33a. However, each end bracket 701 can be manually swung, overcoming the frictional action of spring 701c, to the broken line position of Fig. 33a. In this position the end abutments 701 lie above the top sheet of the stack, exposing the portion of the stack which is normally contacted by the lower portions of

the normally vertical end abutments 701, thus permitting easy removal of the stack endwise without interference by the end abutments.

Dampening mechanism

5 The plate dampening mechanism indicated generally by reference character 50 is mounted between side plates 730, and the dampening mechanism as a whole is slidable downwardly in an inclined path away from the main cylinder 42 to expose a large portion of the surface of the main cylinder for cleaning and for changing or adjusting the lithographic plate, and also to expose the rollers of the dampening mechanism.

10 As shown in Figs. 34 and 35 cross-bars 731 and 732, which extend across the press, carry stationary inclined rack bars 735 adjacent to the inclined lower edges of the side plates 730 of the dampening mechanism. The dampening mechanism is slidably positioned with respect to the rack bars by pilot pins 730a (Fig. 35) which extend from the side frames 730 into grooves 730b in the respective rack bars. The dampening mechanism is movable toward and away from the main cylinder 42 15 by pinions 734 which engage the teeth of rack bars 735. Pinions 734 are fast on a shaft 737 carrying a worm gear 738 which meshes with a worm 739 on a shaft 740 provided with a hand-wheel 741. Rotation of the handwheel 741 thus carries the dampening mechanism to its operative position such as indicated in full lines in Fig. 35 or downwardly and away from the main cylinder to a position such as indicated in broken lines in Fig. 35 which renders both the main cylinder 20 and the rollers of the dampening mechanism readily accessible.

25 The pilot pins 730a, by engaging the ends of the groove 730b stop the sliding movement of the moistening mechanism at its upper and lower extremes.

30 As indicated in Fig. 35, the dampening mechanism includes a water reservoir 750, a fountain roll 751 dipping into the reservoir and driven by shaft 752, a ductor roll 754 mounted on arms 755 which are fast on an oscillating shaft 756, an axially oscillating distributor roll 757 fast on a shaft 758, and two dampening rolls 760 and 761 which frictionally engage the distributor roll 757.

35 The dampening rolls 760 and 761 are each individually held in contact with the lithographic plate segment 43 of main cylinder to dampen all portions of the lithographic plate, and are each individually moved away from the main cylinder so as to avoid dampening any portion of the impression segment 44. Roll 760 is carried by opposite arms 762 which freely pivot on the shaft 758 of the distributor roll, and roll 761 is carried by opposite arms 763 which also freely pivot on the shaft 758.

40 One of the arms 762 and its roll 760 are controlled by a plunger 764 to the lower end of which is connected a cam follower roller 766 which runs on a cam 768, and one of the arms 763 and its roll 761 are controlled by a plunger 765 to the lower end of which is connected a cam follower roller 767 which runs on a cam 769.

45 A cam shaft 770 carrying the cams 768 and 769 is rotated one revolution for each revolution of the main cylinder by connections described below, and cams 768 and 769 are so shaped and positioned on cam shaft 770 that, as the main cylinder rotates, each roll 760 and 761 will move in sequence into contact with the lithographic plate as the leading edge of the plate presents itself, and will move in sequence away from the main

cylinder as the trailing edge of the lithographic plate presents itself. Thus each dampening roll 760 and 761 dampens all portions of the plate and each dampening roll remains away from the main cylinder sufficiently long to avoid contact with the impression segment.

Roll 761 tends to move by gravity toward the main cylinder, and is drawn away from the main cylinder at the appropriate times by the pull of plunger 765 caused by cam 769. Roll 760 is yielding urged toward the main cylinder by a tension spring 771 acting on the arm 762, and is pushed away from the main cylinder by the push of plunger 764 caused by cam 769.

The plungers 764 and 765 are connected to their arms 762 and 763 by screw-threaded connections 764^a and 765^a respectively, so that by rotating the plunger the associated dampening roll can be individually adjusted with respect to the surface of the main cylinder to compensate for wear or change in diameter of each individual dampening roll.

The construction described above for movement of the applicator rolls is especially advantageous in permitting high speed operation with a minimum of noise and vibration.

The several driven parts of the dampening mechanism are adapted to maintain their operative driving connection with the remainder of the press in both the operative position of the dampening mechanism and the lowered or inoperative position, and the timing of the dampening mechanism is not disturbed by shifting it toward or away from the main cylinder.

Drives for elements of the dampening apparatus

As indicated in Fig. 36, a square shaft 775 is mounted in bearings 776 which are stationary so that square shaft 775 does not partake of the shift of the dampening mechanism. Square shaft 775 is continuously in geared connection with the main cylinder through bevel gears 778 and 779, a pinion 780 turning with bevel gear 779, and a pinion 783 meshing with pinion 780 and with the gear 165 on the main cylinder shaft.

Driving power is transmitted to several of the elements of the dampening mechanism from the square shaft 775 by a bevel gear 790 which is slideable lengthwise with the dampening mechanism in splined relation to the square shaft 775, a bevel gear 791 and a shaft 793. The shaft 778 which, as shown in Fig. 35, drives the cams 768 and 769 for swinging the dampening rolls, is shown in Fig. 36 as provided with a worm gear 795 meshing with a worm 797 on shaft 793 so as to be driven thereby. Thus the driving means for the dampening rolls is operatively connected to the main cylinder in all positions of the frame of the dampening mechanism, and the timing of the motion of the dampening rolls with relation to the main cylinder is not disturbed by shifting the dampening mechanism into and out of operative position. Similarly, the other elements of the dampening mechanism which receive their drive from square shaft 775 are continuously operatively connected to the main cylinder.

The shaft 752, Fig. 35, which drives the fountain roll 751 is shown in Fig. 36 as provided with a worm wheel 797 meshing with a worm 798 on shaft 793 so as to be driven thereby.

As shown in Fig. 34, shaft 756 on which the ductor roll 754 is mounted, carries a crank arm 802 adjustably mounted thereon, and a cam follower 803 on the crank arm 802 runs on a cam comprising two angularly adjustable sectors 804 and 805

adjustably secured on a cam shaft 807. These cam sectors 804, 805 are adapted to move the ductor roll 754 to the right, to the position of Figs. 34 and 35 in opposition to a tension spring 806 (Fig. 34) which acts on one of the arms 755. Shaft 752 (Fig. 34) which drives the fountain roll 751, carries a gear 809 meshing with a gear 810 on the cam shaft 807, so as to drive the cam shaft 807.

By variation of the relative positions of cam sectors 804 and 805 the duration of contact of the ductor roll 754 with the fountain roll 751 and with the distributor roll 757 can be suitably varied.

The pitch diameter of driving gear 809 (Fig. 34) is the same as the diameter of the fountain roll 751 (Fig. 35) and the pitch diameter of driven gear 810 on cam shaft 807 is slightly smaller than that of gear 809, so that gear 810 has a few less teeth than gear 809. Thus the time occupied by the cycle of oscillation of the ductor roll 754 does not exactly coincide with the time in which the fountain roll 751 makes one revolution, and a considerable number of oscillations of the ductor roll will intervene between the times when the ductor roll makes contact with any given place on the fountain roll. Similarly, the time required for a complete cycle of oscillation of the ductor roll 754 does not exactly coincide with the time in which one revolution of the distributor roll 757 takes place, and a considerable number of oscillations of the ductor roll similarly intervene between the times when the ductor roll makes contact with any given place on the distributor roll.

The shaft 758 that rotates the distributor roll 757 operates a conventional roll-oscillating device indicated generally in Fig. 36 by the reference character 818, adapted to oscillate the distributor roll axially. Distributor roll shaft 758 is driven by a gear 817 (Fig. 34) a gear 819 meshing with the gear 817, a shaft 821 and a sprocket 820 meshing with a chain 822.

Chain 822 travels in a generally triangular path, as shown in Fig. 34, around sprockets 825, 826 and 827, the run of chain from sprocket 825 to sprocket 826 being parallel to rack 735 so that the driven sprocket 829 remains in mesh with the chain 822 in all positions of the frame of the dampening mechanism.

Sprocket 827 is driven by its shaft 828, a gear 829 on the shaft 828 and a gear 830 on shaft 137.

Inking mechanism

As previously explained, the main press frame includes generally vertical plate sections 25 at opposite sides of the press.

The inking mechanism is carried by two further frames which may be removed from the press.

An upper stationary frame comprising interconnected plates 850 (Fig. 38) rests on cross bars 851, 852 carried by the main frame, and each plate 850 of the upper stationary frame is spaced somewhat inwardly of its adjacent main frame plate 25.

An upper movable frame comprises interconnected plates 855, each of these plates being located between its adjacent upper stationary frame plate 850 and main frame plate 25, and the two interconnected plates 855 of the upper movable frame are pivotally mounted about the axis of the horizontal shaft 857 carried by the upper stationary frame, as indicated in Fig. 38.

The shaft 857 forms the central axis for the drive of mechanism carried by both the upper stationary frame and by the upper movable

frame, and is itself driven by a gear 859 (Fig. 2) and a gear 860 on a shaft 861, gear 860 being driven by the gear 165 that rotates with the main cylinder.

An ink fountain indicated generally at 869 (Fig. 1) carried by the stationary upper frame, is provided with an ink fountain roll 870 which delivers ink to a ductor 880 from which the ink is delivered in succession to a transfer roll 890 and a further transfer roll 891. Ductor roll 880 is swung back and forth between ink fountain roll 870 and transfer roll 890 by means of a cam 881 carried by a continuously rotated shaft 882. The ink transfer mechanism, extending from the ink fountain to and including the transfer roll 891, is carried by the upper stationary frame comprised of plates 850.

The ink transfer roll 891 delivers ink to an oscillating distributor roll 893 on the shaft 857 at the axis of pivotal connection between the upper stationary frame and the upper movable frame.

Ink travels from the distributor roll 893 to a transfer roll 894, an oscillating distributor roll 895, a transfer roll 898, an oscillating distributor roll 900 on shaft 901, a transfer roll 910, an oscillating distributor roll 911, a transfer roll 915, and an oscillating distributor roll 916 on a shaft 917, all of these rolls having their shafts mounted in the upper movable frame, and the distributor roll 893 also having its shaft 857 mounted in the upper stationary frame.

Form rolls 902, 921 and 922 run in frictional contact with the distributor rolls 893, 900 and 916, respectively. The shafts 930, 931 and 932 (Fig. 39) of these form rolls are carried by hangers 935, 936 and 937, respectively, which are provided with enlarged upper ends which pivotally seat within bosses 935^a, 936^a and 937^a, respectively, on the upper stationary frame 850, as more fully described below. This mounting of the form roll hangers permits pivotal movement of the form rolls about the axes of the distributor roll shafts so that the form rolls can move toward and from the main cylinder while remaining in operative contact with their distributor rolls.

Each form roll hanger is secured within its boss on the frame 850 by a detachable plate. Thus Figs. 45 and 46 show the hanger 936 with its head portion rotatably seated within boss 936^a and secured in this position by a detachable plate 936^b.

Each form roll 920, 921 and 922 has its shaft mounted in its hangers 935, 936 or 937 by an adjustable mounting such as shown in Figs. 45 and 46 wherein the shaft 931 of form roll 921 is shown as mounted in a block 942. Block 942 is adjustable lengthwise of the bracket 936 by a set screw 943 to adjust the form roll into proper engagement with its cooperating distributor roll.

The pressure of contact of the form rolls 920, 921 and 922 against the plate segment of the main cylinder can be adjusted by set screws 944 (Fig. 39) against which the hangers 935, 936 and 937 abut in the operative positions of the form rolls.

In normal running of the press while the sheets are being properly fed, each form roll 920, 921, 922 is in frictional contact with the lithographic plate on the passing lithographic plate segment 43 of the main cylinder.

During passage of the impression segment 44 of the main cylinder, cam follower disks 930^a, 931^a and 932^a (Fig. 39) on the form roll shafts 930, 931 and 932 make contact with a cam 940 on the main cylinder with the result of shifting the

form rolls individually out of position to contact with the impression segment 44.

Cam 940 on the main cylinder overlaps all of the impression segment 44 and also the two gaps between the impression segment 44 and the lithographic plate segment 43 so that the form rolls neither contact with the impression segment nor tend to drop into the gaps between segments of the main cylinder but operatively engage only the lithographic plate segment 43. Each form roll is individually shifted out of operative position by the cam 940 as the form roll is reached by the trailing end of the lithographic plate segment 43 and each form roll is automatically returned into operative position by a tension spring 941 as the form roll is reached by the beginning end of the lithographic plate segment 43. Fig. 39 shows all three form rolls simultaneously held out of contact with the impression segment by passage of the cam 940.

Access to normally inaccessible parts of the press

The upper movable frame comprising the plate members 855, 855, carrying ink transfer mechanism and distributor rolls for the main cylinder, and also carrying inking mechanism for a supplemental printing cylinder as hereinafter described, can be shifted about its pivot 851 to the elevated position of Fig. 38 to expose ordinarily inaccessible parts.

As indicated above, the distributor rolls 893, 900 and 916 are carried by the movable upper frame 855, and when this frame is swung upwardly about shaft 851 both distributor rolls 900 and 916 accompany the upper movable frame and leave their corresponding form rolls 921 and 922.

Bosses 936^a and 937^a, which pivotally support the hangers 936 and 937 of form rolls 921 and 922, and also the detachable plates, such as plate 936^b, which retain the form roll hangers in place in these bosses, are provided with slots indicated at 938 (Fig. 46). These slots have sides which are arcuate and concentric with shaft 851, and permit the distributor roll shafts 901 and 917 to enter and leave these slots as the upper frame 855 swings around shaft 851.

The upper ends of hangers 936 and 937 are also forked to receive the distributor roll shafts 901 and 917 at the axes of pivotal movement of these hangers when the upper movable frame is in its lower position, and these forked portions of hangers 936 and 937 are shaped so as not to interfere with the entrance or exit of shafts 901 or 917 into or from the bosses 936^a and 937^a in any of the angular positions of the hangers 936 and 937.

Rods 840 (Fig. 38), at opposite sides of the press, are pivotally connected at their lower ends to the cross bar 852 of the stationary main frame 25, and are threaded into internally threaded worm wheels 842 (Fig. 38a). Worm wheels 842 are engaged by worms 843 on a cross shaft 844, each worm wheel and the shaft 844 being secured to the upper movable frame 855 by a retaining bracket 845 pivotally mounted on the frame 855 at 846. A crank arm 847 on shaft 844 enables the worm wheels 842 to be rotated to screw them up and down the rods 840, thus raising and lowering the upper movable frame 855 and the parts carried thereby. In the raised position of Fig. 38 many normally inaccessible parts of the press are exposed, for example, the form rolls for the main cylinder, and the supplemental printing cylinder subsequently described.

Control of inking mechanism

The inking mechanism is prevented from inking the lithographic plate during continued running of the machine after a sheet has failed to be fed.

Referring to Fig. 39, each of the hangers 935, 936 and 937 shown therein for carrying the form rolls is provided with a cam follower roller 966. A segmental plate 952 is slidable in an arcuate path upon pins 953 which are mounted in the upper stationary side plate 859 and extend through arcuate slots 954 in the segmental plate. Cut-out portions 955 of the segmental plate 952 normally clear the cam follower rollers 966 and are provided with inclined cam surface portions 956^a adapted to contact with and lift the cam follower rollers 966 when the segmental plate 952 is shifted in a clockwise direction from Fig. 39, and so shift the form rolls around their respective distributor rolls and out of contact with the lithographic plate.

Segmental plate 952 is connected by a link 960 to a bell crank 961 which is fast on a shaft 962 rotatable in the upper stationary side plate 859, and the left end of bell crank 961 is formed as a handle 961^a for convenient resetting of the mechanism.

A lever 965 is forked at its lower end so as to straddle a squared outer end of the shaft 962 which carries the bell crank 961, and is pivotally mounted thereon by means of a pin 965^a so that its upper portion can swing toward and away from the observer in Fig. 39. The upper end of lever 965 carries a cam follower roller 966 adapted to make contact with a cam surface 967 on a plate cam 968 which is carried by the continuously rotating shaft 882 (Figs. 39 and 1). A coil spring 970 acting on the lever 965 and upon an enlarged head 965^b of the pivot pin 965^a yieldingly urges the upper end of the lever 965 away from the observer in Fig. 39 and toward the left in Fig. 40 to carry the cam follower roller 966 into position to be engaged by cam surface 967. When this engagement takes place the cam surface 967 turns the lever 965, shaft 962 and bell crank 961 counterclockwise from Fig. 39, thrusting the connecting link 960 and segmental plate 952 to the right thus throwing the form rolls out of operative position.

In normal feeding of the sheets, such throwing out of the form rolls is prevented by electrically actuated mechanism actuated by the application of pressure to the offset cylinder and hence, indirectly, by the continuous proper feeding of sheets to the press.

A solenoid 980 has its movable armature 981 connected by link 982 to a lever 983 which is fast on a pivotally mounted shaft 984. As shown in Fig. 40, a flat surface 985 on the shaft 984 is adapted to bear as a cam, against the lower end of lever 965 when the solenoid 980 is energized, tilting the lever 965 clockwise into the position of Fig. 40 and thus holding the cam follower roller 966 out of contact with the cam surface 967. As indicated in Fig. 37, solenoid 980 is in series with the previously mentioned limit switch 390^b which is closed when pressure is applied to the offset cylinder and open when pressure is not applied to the offset cylinder.

When the limit switch 390^b opens upon failure of feed and consequent release of pressure at the offset cylinders and solenoid 980 is accordingly de-energized, the cam follower roller 966 is allowed to be engaged by cam surface 967, and

the form rolls are thrown out to inoperative position as above described.

In starting the press, it is advantageous to be able to allow the form rolls to function before pressure is applied to the offset cylinder, at which time the solenoid 980 is de-energized because the limit switch 390^b is open. Throwing out of the form rolls may be prevented during this period by manually rotating the shaft 984 by means of a knurled knob 990 to bring the parts manually to the position of Fig. 40.

Manual rotation of the shaft 984 may also be employed to disconnect the follower roller 966 from the cam surface 967 in returning the form rolls to operative position. When the follower roller 966 has been disengaged from the cam surface 967, the form rolls may be returned to operative position by manually lifting the handle portion 961^a of the bell crank lever 961.

A manually controlled switch 980^a, in series with solenoid 980, is normally closed but may be opened to prevent this solenoid from being energized, as for instance when it is desired that the form rolls shall immediately be thrown out of operative position notwithstanding the main and offset cylinders are not separated.

Supplemental mechanism for offsetting onto impression segment

The press includes supplemental mechanism which can be thrown into and out of operation at will, for offsetting an image onto the impression segment 44 of the main cylinder so that this image can be transferred to the sheet by the impression segment while the other face of the sheet is receiving its printed image from the offset cylinder 40.

This supplemental mechanism is particularly useful and effective in cases in which the whole or a large part of one surface of the sheet is to be printed by means of the offset cylinder and a relatively small amount of printing is to be applied to the other or back face of the sheet.

The press thus includes the supplemental cylinder 60 previously referred to, adapted to offset an image onto the impression segment 44. The cylinder 60 may, for example, carry a lithographic plate and have associated therewith dampening and inking mechanism for the lithographic plate, so as to offset a lithographic image upon the impression segment 44. Or the cylinder 60 may be surfaced with rubber or suitable plastic and serve as an offset cylinder to receive an inked image and then transfer the same to the impression segment 44. Again, the cylinder 60 may be arranged to carry letter press type and transfer the image of these type onto the impression segment 44.

In general, any known kind of removable image-carrying or image-producing covering or partial covering may be applied to the cylinder 60, and it is one of the advantages of the invention that changes may readily be made in such covering or partial covering of the supplemental cylinder 60 without requiring dismantling of the main portions of the press.

For many purposes a satisfactory supplemental printing on the back face of the sheet can be accomplished by application to the supplemental cylinder 60 of a simple, easily removable rubber plate formed with raised type, indicated diagrammatically at 1012 in Fig. 41.

As shown in Fig. 41 the supplemental cylinder 60 is mounted on a sleeve 1000 which is rotatable

in roller bearings 1001 on a shaft 1002 which extends between opposite side frame members 25 of the press. A gear 1000^a on sleeve 1000 meshes with main gear 165, as indicated in Fig. 2, to drive the supplemental cylinder 60. A further gear 1000^b on sleeve 1000 serves to drive a form roll 1046, subsequently described, for the supplemental cylinder.

A collar 1004 which is keyed to the sleeve 1000 at 1005 carries a worm gear 1007. The cylinder 60 is rotatable upon the sleeve 1000 and may be adjusted circumferentially of the sleeve 1000 by rotation of a worm 1008 provided with a squared projecting portion 1009 and rotatably mounted in a bracket 1010 on the end face of the cylinder 60 so as to mesh with worm gear 1007. Thus the rubber plate 1012 on the surface of cylinder 60 can be brought into any desired position with respect to the length of the impression segment by rotatably adjusting the cylinder 60 on its sleeve 1000. The shaft 1002 on which the supplemental cylinder 60 rotates is provided with eccentric portions 1020 suitably mounted in bearings in side frame elements of the press.

As indicated in Fig. 43, a cam 1022 on the main cylinder shaft 166 is engageable with a cam follower roller 1024 on a pressure fork 1025, and the pressure fork is adjustably connected by threaded rods 1027 and a link 1028 to a collar 1029 which is fast on the shaft 1002.

The cam 1022 is so positioned on the main cylinder shaft 166 that in the position of Fig. 43 which corresponds to passage of the lithographic plate segment 43 past the supplemental cylinder 60 the supplemental cylinder is rocked about eccentric portions 1020 away from the cylinder, and thereby held out of printing engagement with the lithographic plate segment.

After the lithographic plate has passed the supplemental cylinder 60, the low surface of cam 1022 is presented to the cam follower roller 1024, enabling a spring 1032 to retain the pressure fork 1025 in its right-hand position and hold the supplemental cylinder 60 in yielding engagement with the impression segment of the main cylinder. The pressure of the supplemental cylinder 60 against the impression segment may be adjusted by adjustment of the threaded rods 1027.

An ink fountain indicated generally at 1040 and carried by the movable upper frame 855 is provided with an ink fountain roll 1041 which delivers ink to a doctor roller 1043 from which the ink is delivered in succession to a transfer roll 1045 and the previously-mentioned form roll 1046.

Transfer roll 1045 and form roll 1046 are mounted on slides in the upper movable frame 855 and in the upper stationary frame 850, respectively, these slides permitting these rolls to accommodate themselves to the eccentric swinging motion of supplemental cylinder 60 as the latter is moved to and from the main cylinder.

Thus, Fig. 47 shows the shaft 1045^a of transfer roll 1045 mounted in a bearing block 1045^b which is slideable in side guides 1045^c carried by the upper movable frame 855. Transfer roll 1045 normally rests by gravity against form roll 1046. When, however, the upper movable frame 855 is raised, a pin 1045^d fixed therein engages the block 1045^b and carries the transfer roll 1045 upwardly with the frame 855.

The shaft 1046^a of form roll 1046 carries a gear 1050 (Fig. 48) adapted to mesh with the previously-mentioned gear 1000^b (Fig. 41) so as to drive the form roll 1046.

As indicated in Figs. 47 and 48 the shaft 1046^a of form roll 1046 is mounted in a bearing block 1046^b which is shiftable within a slide 1046^c by means of a screw 1046^d. Slide 1046^c is slidably mounted in side guides 1046^e carried by upper stationary frame 850.

A follower roller 1052 carried by slide 1046^d and running in contact with a cylindrical surface 1053 which rotates with the supplemental cylinder 60 positions the slide 1046^c with respect to the supplemental cylinder as the supplemental cylinder moves in and out toward and from the main cylinder. By adjustment of the screw 1046^d the form roll 1046 may be maintained at any desired distance from the bare surface of cylinder 60 to accommodate any desired thickness of type plate 1012 or other image-carrying or image-forming covering that is carried by supplemental cylinder 60.

20 The supplemental cylinder can be retained out of operative engagement with the impression segment by mechanism subsequently described. At times it is also desirable to throw the form roll 1046 out of operative engagement with the 25 supplemental cylinder. A lever 1054 is pivotally mounted at 1055 upon the upper stationary frame 850. The right end of this lever is adapted to engage with the block 1046^b to lift this block and thus raise the form roll 1046. A rod 1056, extending from side to side of the upper stationary frame, and provided with a handle 1057, carries a cam 1058 engageable with the left end of lever 1054. Rotation of the rod 1056 causes the cam 1058 to rotate the lever 1054 and hold 30 it in position to maintain form roll 1046 out of operative engagement with the supplemental cylinder 60.

As previously explained, the impression segment 44 is removable and various impression segments may be interchanged. For use in carrying an image received from supplemental cylinder 60, the impression segment should have an ink-receptive surface. An impression segment having a hard metal surface is satisfactory for many kinds of work, while for other work it may be advantageous to substitute an impression segment having a surface of rubber, hard plastic, or other ink-receptive composition.

50 *Control of supplemental offsetting mechanism in accordance with sheet feed and pressure at offset cylinder*

The supplemental cylinder 60 is prevented from offsetting onto the impression segment during continued running of the machine after the machine has failed to be fed in the normal manner.

Referring to Figs. 43 and 44 the supplemental cylinder pressure fork 1025 carries a down-turned projecting portion 1060 to which is secured an adjustable stop element 1061. A lever 1063 is pivotally mounted at 1064 on a bracket 1065 extending from the main frame, and the upper end of lever 1063 is yieldingly urged by a spring 1067 into a position such as shown in Fig. 44 in which, at the outward throw of the pressure fork, this upper end of lever 1063 can engage the right side of stop element 1061 as shown in Fig. 43. With the lever thus engaging the right surface of stop element 1061, the supplemental cylinder is locked away from the main cylinder.

A solenoid 1080 has its movable armature 1081 connected by a link 1082 to the lower end of lever 75 1063 so that, upon energization of the solenoid,

lever 1063 is swung to carry its upper end out of the path of stop element 1061.

Solenoid 1080 is connected in parallel relation with the previously described solenoids 540 and 980 and is under the control of limit switch 390^b.

As described above, when the offset cylinder moves out of pressure relation to the main cylinder upon failure of feed, the limit switch 390^b opens. In the open condition of limit switch 390^b, the solenoid 1080 is prevented from being energized and lever 1063 is thereupon free to engage stop element 1061 and lock the supplemental cylinder away from the main cylinder.

A manually controlled switch 1089^a, in series with solenoid 1080, is closed when it is desired that the supplemental offsetting cylinder shall operate, but may be opened to prevent this solenoid from being energized when it is desired that the supplemental offsetting cylinder shall be inoperative, notwithstanding closure of limit switch 390^b.

Counter, and control of counter in accordance with sheet feed and pressure at offset cylinder

An electrically actuated counter 1092 is connected in parallel with the solenoids 360, 540 and 1080, as shown in Fig. 37, and counts each printing impression made by the main cylinder of the press.

The actuation of the counter is by an electrical impulse sent through its circuit by the photoelectric relay 380 when the beam of light at photoelectric cell 371 is interrupted as a sheet is fed to the main and offset cylinders.

The counter is prevented from being actuated unless pressure is applied to the offset cylinder. Since the limit switch 390^a is open when pressure is not applied to the offset cylinder, this condition prevents completion of a circuit through the counter.

It will be observed that upon failure of sheet feed the continued running of the chains 480 of the first conveyor will bring the gripper bar 33 between the lamp 370 and photoelectric cell 371, repeatedly breaking the beam of light and repeatedly closing the contacts D and F of the photoelectric relay 380. This effect unless modified would cause the counter 1092 to count the passage of gripper bars 33 which carried no sheets, but the above-described limit switch opens and thus intervenes to prevent counting. While the first empty gripper bar which lacks a sheet will be counted, the counter will then cease counting. If extreme accuracy of a count is desired the operator can make a practice of setting the counter back one unit upon failure of feed.

A manually controlled switch 1092^a, in series with counter 1092, is normally closed but may be opened to prevent operation of the counter.

Control of sheet feed

The press is preferably provided with means for automatically stopping feed of sheets when a sheet fails to be properly fed, and in the preferred form of such mechanism, indicated in the diagram of Fig. 37^a, the feed of sheets is automatically stopped as a result of separation of the combined plate and impression cylinder and the offset cylinder. Provision is also preferably made for permitting feed of the sheets notwithstanding the separation of the combined and offset cylinders.

As indicated in the diagram of Fig. 37^a, the air pump 1060, which provides suction for the picker

nozzles 56 and air pressure for the air blast nozzles 140, is driven by an electric motor 1061 receiving its current through contacts 1065, 1065 and 1066, 1066 of a magnetically closed switch 1070.

5 A push button starting switch 1072 is adapted to energize the magnetic coil of switch 1070 to cause the circuit of the feeder motor to become closed through contacts 1065 and 1066. Closing of the motor switch contacts 1065 and 1066 is also accompanied by closing of holding circuit contacts 1075 and 1076 adapted to establish a holding circuit through the magnetic coil of switch 1070 and through a push button stop switch 1078, thus to maintain the motor circuit closed after release of the starting switch 1072 and permit the motor to be stopped by pressing the stop switch 1078.

The limit switch 390^c which opens, as previously explained, when pressure is not applied to the offset roll, is interposed (Fig. 37^a) in the holding circuit of the motor switch 1070. A manually operable switch 1079 is also interposed in this holding circuit, in parallel with the limit switch 390^c.

25 With the manual switch 1079 closed, the holding circuit will be automatically established through the switch 1070 upon closing the push button starting switch 1072, notwithstanding the limit switch 390^c may be open as a result of separation of the main and offset cylinders. With the press and the conveyor of the feeder running, and the feeder pump motor also working, sheets may be fed through the press in order to make certain that all parts of the press are properly 30 adjusted to accommodate the sheets.

35 Closing the switch 342^a, Fig. 37, will energize the solenoid 342 to effect connection between the pressure fork 325 and the offset cylinder, and thus bring the offset cylinder into pressure relation to the combined cylinder, whereupon printing will begin and the several limit switches including limit switch 390^c will close. Thereupon the operator can open manual switch 1079, Fig. 37^a, and further operation of the feeder pump motor will depend upon limit switch 390^c remaining closed. At any time thereafter at which a sheet fails to be properly fed, and the offset and combined cylinders separate, limit switch 390^c will open and automatically stop the feeder pump motor 1061 and feeder air pump 1060. This feed of further sheets is thus instantly stopped, although the pickers 56 and conveyors of the feeder continue to be driven in timed relation to the main cylinder and the various conveyors of the press by the driving connections described in said application Serial No. 590,225.

Review of control circuit wiring diagram

Many of the elements of the control circuit and their functions have been described above. Referring to Fig. 37, a suitable alternating current line is shown as adapted to supply current to the electric lamp 370, the photoelectric cell 371, the photoelectric relay 380 and a photoelectric 60 amplification network indicated diagrammatically at 1090, under the control of the manually operated switch 1091.

The photoelectric amplification network 1090 is of such character as to transmit amplified current to the relay 380 such as to close the circuit between contacts D and F upon the interruption of the beam of light normally cast by lamp 370 upon the cell 371.

70 The cell 371, relay 380 and network 1090 may for example together constitute the device known

as the General Electric Company "Photoelectric Relay CR7505 K100 G2," only those parts of that device that are necessary for an understanding of this invention being shown herein.

As previously described, and as will be apparent from the diagram of Fig. 37, the latch solenoid 360, the numbering unit solenoid 540, the supplemental offsetting cylinder solenoid 1080, and the counter 1092 are connected in parallel so that each is adapted to receive an impulse when the photoelectric relay 380 operates to close the circuit between contacts D and F in the event that limit switch 390^a is closed.

Manually controlled switches 540^a, 1080^a, and 1092^a, connected in series with the solenoids 540, 1080 and counter 1092 respectively, are adapted to be opened so as to prevent operation of any of these elements as desired. Thus, the press may be run without its numbering unit functioning, or without its supplemental offsetting cylinder functioning, or without its counter functioning, or without any or all of these functioning, as desired.

As explained above, the push button switch 342^a is depressed to energize solenoid 342 to pull the pin 331 to the right in Fig. 13, carrying it into the path of the pressure fork shoulder 334, thus effecting an initial connection between the pressure fork and the offset cylinder, a connection which is maintained by pressure of the pressure fork shoulder 334 upon the pin 331 until failure of a sheet to be fed causes the latch 350 to fail to be engaged and held in the recess 353 of the pressure fork.

The operator can release the push button switch 342^a as soon as a properly fed sheet has caused the latch 350 to hold the pressure fork.

Failure of feed of a sheet causes release of pressure upon the offset cylinder and causes limit switches 390^a, 390^b and 390^c to open.

The open condition of limit switch 390^a (Fig. 37) prevents energization of solenoid 360 and prevents latching of the pressure fork in its lower or pressure-applying position unless the offset cylinder has been moved into pressure relation to the main cylinder by means of the connecting pin 331, and also prevents energization and operation of the counter 1092.

The open condition of limit switch 390^b prevents energization of solenoid 540 and prevents operation of the numbering mechanism, prevents energization of solenoid 1080 and prevents offsetting from the supplemental offsetting cylinder.

The open condition of limit switch 390^b (Fig. 37) prevents energization of solenoid 602 and prevents automatic lowering of the pile delivery table. The open condition of limit switch 390^b also prevents energization of solenoid 980 and so prevents operative contact of the form rolls with the plate segment of the main cylinder excepting in the event that the knob 990 (Fig. 39) is turned and held by hand to permit such operative engagement.

The open condition of limit switch 390^c (Fig. 37^a) breaks the holding circuit of the feeder pump motor switch (unless the manual switch 1079 is closed), and so stops the feed of sheets. Feed of sheets may, however, be carried on in the open condition of limit switch 390^c by having the switch 1079 closed.

I claim:

1. A printing press of the type including a combined plate and impression cylinder having segments constituting a lithographic plate holder

and an impression surface, an offset cylinder movable toward and away from said combined plate and impression cylinder, a cam for pressing the offset cylinder against said combined plate and impression cylinder, a plunger connected to operate said cam, a second cam rotatable in synchronism with said combined plate and impression cylinder for operating said plunger, said second cam having a shape adapted to cause the two cylinders to be held together during the presentation of the lithographic plate to the offset cylinder and adapted to allow complete separation of the two cylinders to prevent offsetting of the image from the offset cylinder onto the impression surface in the absence of a sheet to be printed, and latching means responsive to the presence of a sheet to be printed for causing the offset cylinder to be held in printing contact with the impression segment of said combined plate and impression cylinder so that no more than a relatively slight separation and approach of the axes of the cylinders occurs in normal printing, the press being characterized in that said latching means includes a latch applied to said plunger, so that in normal operation when the supply of sheets to be printed does not fail the plunger moves only through such portion of the length of its stroke as effects said relatively slight approach of the axes of said cylinders.

2. A printing press of the type including a combined plate and impression cylinder having segments constituting a lithographic plate holder and an impression surface, an offset cylinder movable toward and away from said combined plate and impression cylinder, a cam for pressing the offset cylinder against said combined plate and impression cylinder, a plunger connected to operate said cam, a second cam rotatable in synchronism with said combined plate and impression cylinder for operating said plunger, said second cam having a shape adapted to cause the two cylinders to be held together during the presentation of the lithographic plate to the offset cylinder and adapted to allow complete separation of the two cylinders to prevent offsetting of the image from the offset cylinder onto the impression surface in the absence of a sheet to be printed, and latching means responsive to the presence of a sheet to be printed for causing the offset cylinder to be held in printing contact with the impression segment of said combined plate and impression cylinder so that no more than a relatively slight separation and approach of the axes of the cylinders occurs in normal printing, the press being characterized in that said latching means includes a latch applied to said plunger, so that in normal operation when the supply of sheets to be printed does not fail the plunger moves only through such portion of the length of its stroke as effects said relatively slight approach of the axes of said cylinders, the latch being adjustable with respect to the direction of movement of said plunger, to vary the amount of such relatively slight separation and approach.

3. A printing press of the type including a combined plate and impression cylinder having segments constituting a lithographic plate holder and an impression surface, an offset cylinder movable toward and away from said combined plate and impression cylinder, a cam for pressing the offset cylinder against said combined plate and impression cylinder, a plunger connected to operate said cam, a second cam rotatable in syn-

35

chronism with said combined plate and impression cylinder for operating said plunger; said second cam having a shape adapted to cause the two cylinders to be held together during the presentation of the lithographic plate to the offset cylinder and adapted to allow complete separation of the two cylinders to prevent offsetting of the image from the offset cylinder onto the impression surface in the absence of a sheet to be printed, and latching means responsive to the presence of a sheet to be printed for causing the offset cylinder to be held in printing contact with the impression segment of said combined plate and impression cylinder so that no more than a relatively slight separation and approach of the axes of the cylinders occurs in normal printing; said latching means including a movable latch applied to said plunger, so that in normal operation when the supply of sheets to be printed does not fail the plunger moves only through such portion of the length of its stroke as effects said relatively slight approach of the axes of said cylinders, means for guiding said latch in a direction transverse to the direction of movement of the plunger, and means for adjusting the position of said guiding means longitudinally of the direction of movement of said plunger.

4. A sheet-fed lithographic printing press comprising a combined plate and impression cylinder including a lithographic plate segment and an impression segment, inking and wetting means operative upon the lithographic plate segment, an offset cylinder of substantially half of the diameter of the combined cylinder and adapted to press against said combined cylinder, sheet-feeding means constructed and arranged to introduce a sheet between said cylinders at each presentation of the impression segment to the offset cylinder and means for transferring an inked image to the impression segment preparatory to presentation of the impression segment to the offset cylinder and sheet, said transferring means including a supplemental cylinder of substantially the diameter of the offset cylinder and means for bringing said supplemental cylinder into printing engagement with the impression segment but not the plate segment of the combined cylinder, and means responsive to failure of feed of a sheet for preventing engagement of the supplemental cylinder and the impression segment.

5. A sheet-fed lithographic printing press comprising a combined plate and impression cylinder including a lithographic plate segment and an impression segment, inking and wetting means operative upon the lithographic plate segment, an offset cylinder of substantially half of the diameter of the combined cylinder and adapted to press against said combined cylinder, sheet-feeding means constructed and arranged to introduce a sheet between said cylinders at each presentation of the impression segment to the offset cylinder and means for transferring an inked image to the impression segment preparatory to presentation of the impression segment to the offset cylinder and sheet, said transferring means including a supplemental cylinder of substantially the diameter of the offset cylinder and means for bringing said supplemental cylinder into printing engagement with the impression segment but not the plate segment of the combined cylinder, a photoelectric cell responsive to proper feed of a sheet, an electric cir-

36

cuit controlled by said photoelectric cell and means controlled by said circuit for preventing printing engagement of the supplemental cylinder and the impression segment upon failure of feed of a sheet.

6. A sheet-fed lithographic printing press comprising a combined plate and impression cylinder including a lithographic plate segment and an impression segment, inking and wetting means operative upon the lithographic plate segment, an offset cylinder of substantially half of the diameter of the combined cylinder and adapted to press against said combined cylinder, sheet-feeding means constructed and arranged to introduce a sheet between said cylinders at each presentation of the impression segment to the offset cylinder and means for transferring an inked image to the impression segment preparatory to presentation of the impression segment to the offset cylinder and sheet, said transferring means including a supplemental cylinder of substantially the diameter of the offset cylinder and means bringing said supplemental cylinder into printing engagement with the impression segment but not the plate segment of the combined cylinder, means for maintaining separation of the supplemental cylinder and the combined cylinder and means for rendering said separation-maintaining means effective upon failure of feed of a sheet.

7. A sheet-fed lithographic printing press comprising a combined plate and impression cylinder including a lithographic plate segment and an impression segment, inking and wetting means operative upon the lithographic plate segment, an offset cylinder of substantially half of the diameter of the combined cylinder and adapted to press against said combined cylinder, sheet-feeding means constructed and arranged to introduce a sheet between said cylinders at each presentation of the impression segment to the offset cylinder and means for transferring an inked image to the impression segment preparatory to presentation of the impression segment to the offset cylinder and sheet, said transferring means including a supplemental cylinder of substantially the diameter of the offset cylinder and means for bringing said supplemental cylinder into printing engagement with the impression segment but not the plate segment of the combined cylinder, means for maintaining separation of the supplemental cylinder and the combined cylinder, means for rendering said separation-maintaining means effective upon failure of feed of a sheet, and manually controlled means for rendering said separation-maintaining means effective notwithstanding the proper feed of a sheet.

8. A sheet-fed lithographic printing press comprising a combined plate and impression cylinder including a lithographic plate segment and an impression segment, inking and wetting means operative upon the lithographic plate segment, an offset cylinder of substantially half of the diameter of the combined cylinder and adapted to press against said combined cylinder, sheet-feeding means constructed and arranged to introduce a sheet between said cylinders at each presentation of the impression segment to the offset cylinder, means for transferring an inked image to the impression segment preparatory to presentation of the impression segment to the offset cylinder and sheet, said transferring means including a supplemental cylinder of substantially the diameter of the offset cylinder and means for bringing said supplemental cylinder into printing engagement with the impression segment but not the plate segment of the combined cylinder, an electric circuit controlled by a photoelectric cell responsive to proper feed of a sheet, and means for preventing printing engagement of the supplemental cylinder and the impression segment upon failure of feed of a sheet.

ing said supplemental cylinder into printing engagement with the impression segment but not the plate segment of the combined cylinder, means for effecting separation of the offset cylinder and impression segment on failure of a sheet and means for maintaining said supplemental cylinder out of printing engagement with the impression segment in the event of such separation of the offset cylinder and impression segment.

9. A sheet-fed lithographic printing press comprising a combined plate and impression cylinder including a lithographic plate segment and an impression segment, inking and wetting means operative upon the lithographic plate segment, an offset cylinder of substantially half of the diameter of the combined cylinder and adapted to press against said combined cylinder, sheet-feeding means constructed and arranged to introduce a sheet between said cylinders at each presentation of the impression segment to the offset cylinder and means for transferring an inked image to the impression segment preparatory to presentation of the impression segment to the offset cylinder and sheet, said transferring means including a supplemental cylinder of substantially the diameter of the offset cylinder and means for bringing said supplemental cylinder into printing engagement with the impression segment but not the plate segment of the combined cylinder, means for effecting separation of the offset cylinder and impression segment on failure of feed of a sheet, means for maintaining said supplemental cylinder out of printing engagement with the impression segment in the event of such separation of the offset cylinder and impression segment, and manually controlled means for causing said maintaining means to be effective notwithstanding normal feed of sheets and normal engagement of the offset and combined cylinders.

10. In a sheet-fed lithographic press, a combined plate and impression cylinder including a lithographic plate segment and an impression segment, an offset cylinder normally pressed against the combined cylinder, a gripper bar adapted to carry the leading edge of a sheet, conveyors arranged to carry the gripper bar in an endless path from a sheet-receiving position to said offset cylinder and back to said sheet-receiving position, said offset cylinder being recessed to permit the gripper bar to enter between said cylinders, means for applying pressure between the cylinders during presentation of the plate segment to the offset cylinder, a latch adapted to hold said cylinders in pressure relation during presentation of the impression seg-

ment to the offset cylinder, means tending to urge said latch to a non-holding position, means establishing a light beam intersecting the path of said gripper bar, a photoelectric cell disposed to receive said beam, an electrical latch-actuating circuit controlled by said cell and arranged to move the latch to holding position upon interruption of the beam, latch-retaining means effective during presentation of the impression segment to the offset cylinder to retain the latch in its holding position in the event said latch is then in its holding position, said light beam intersecting the path of the gripper bar at a sufficient distance from the offset cylinder so that interruption of the beam by an empty gripper bar ceases before presentation of the impression segment to the offset cylinder, whereby in the event of failure of feed the latch occupies a non-holding position upon such presentation of the impression segment.

ROY ABERLE.
